(57) **CLAIM**

We claim the ornamental design for an electric scooter, as shown and described.

DESCRIPTION

FIG. 1 is a front perspective view of the electric scooter showing the design.

FIG. 2 is a rear perspective view of the electric scooter showing the design.

FIG. 3 is a front elevational view of the electric scooter showing the design.

FIG. 4 is a rear elevational view of the electric scooter showing the design.

FIG. 5 is a left side elevational view of the electric scooter showing the design.

FIG. 6 is a right side elevational view of the electric scooter showing the design.

FIG. 7 is a top plan view of the electric scooter showing the design; and,

FIG. 8 is a bottom plan view of the electric scooter showing the design.

Portions of the electric scooter shown in broken lines form no part of the claimed design.

1 Claim, 5 Drawing Sheets
